Primary Examiner — Cynthia Ramirez*Assistant Examiner* — Llorellys Martinez-Rivera(74) *Attorney, Agent, or Firm* — Finnegan, Henderson, Farabow, Garrett & Dunner, LLP(57) **CLAIM**

The ornamental design for a headlamp, as shown and described.

DESCRIPTION

FIG. 1 is a front left perspective view of a headlamp showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom view thereof.

The claimed design comprises the mirror images of FIGS. 1 through 7 which are not shown.

The broken lines illustrate portions of the headlamp which form no part of the claimed design.

1 Claim, 7 Drawing Sheets(56)
